(57) **CLAIM**

We claim the ornamental design for an electrical receptacle,
as shown and described.

DESCRIPTION

FIG. 1 is a perspective view of an electrical receptacle
according to a first embodiment of our new design.

FIG. 2 is a front view thereof.

FIG. 3 is a left side view thereof.

FIG. 4 is a right side view thereof.

FIG. 5 is a top view thereof.

FIG. 6 is a bottom view thereof.

The rear view of the first embodiment forms no part of the
design and is omitted.

FIG. 7 is a perspective view of an electrical receptacle
according to a second embodiment of our new design.

FIG. 8 is a front view thereof, the left side, right side, top,
and bottom views, respectively, of the second embodiment
being identical to the left side, right side, top, and bottom
views of the first embodiment.

The rear view of the second embodiment forms no part of the
design and is omitted.

FIG. 9 is a perspective view of an electrical receptacle
according to a third embodiment of our new design.

FIG. 10 is a front view thereof, the left side, right side, top,
and bottom views, respectively, of the third embodiment
being identical to the left side, right side, top, and bottom
views of the first embodiment.

The rear view of the third embodiment forms no part of the
design and is omitted.

FIG. 11 is a perspective view of an electrical receptacle
according to a fourth embodiment of our new design; and,
FIG. 12 is a front view thereof, the left side, right side, top,
and bottom views, respectively, of the fourth embodiment
being identical to the left side, right side, top, and bottom
views of the first embodiment.

The rear view of the fourth embodiment forms no part of the
design and is omitted.

(Continued)

The broken lines in the drawings are for the purpose of illustrating environmental structure and form no part of the claimed design.
